COMBINED HAIR BAND AND SUNGLASSES

Siegfried Behr, Flushing, N.Y.

Application December 1, 1958, Serial No. 53,588

Term of patent 14 years

(Cl. D57—1)

Fig. 1 is a front elevational view of a combined hair band and sunglasses, showing my new design.

Fig. 2 is a side elevational view thereof.

Fig. 3 is a top plan view thereof.

I claim:

The ornamental design for a combined hair band and sunglasses, as shown.
